tion of Delaware

Application July 13, 1940, Serial No. 345,257

6 Claims. (Cl. 178—42)

The present invention relates to printing telegraph apparatus and more particularly to automatic paper feeding mechanisms therefor.

The principal object of the present invention is to provide in a printing telegraph receiver having a line feeding mechanism responsive to code combinations of signal impulses a means for effecting automatically through the instrumentality of said line feed mechanism a variable additional number of consecutive line feed operations under the control of the record strip.

A feature of the invention resides in employing a standard line feed mechanism of a page printer, not only for normal line feed operation, but also for multiple line feed or "vertical tabulation."

Another feature resides in controlling a vertical tabulator for a page printer through the instrumentality of the clutch throwout lever of the main shaft clutch.

When using record material comprising a series of blank forms of the same standard length and having preprinted headings, it is desirable to provide in page printers, mechanism for exercising control over the proper feeding of the forms into printing position. The messages on each form, of course, may contain different numbers of recorded lines, and accordingly, before the first line of the next message may be printed, an additional feed must be imparted to the preceding message in order to bring the next form into proper printing position. This additional feed must be of such a length for each message, that forms of standard length will be obtained for said various length messages. Moreover, the additional feed is a complementary additional one since it completes the fixed number of line feeds per preprinted form. Specifically, the present invention is disclosed as embodied in a telegraph printer of the type shown in U. S. Patent 1,904,164, and for achieving the object of the invention, a special signal, which will be identified herein as the "vertical tabulator" signal, controls the selection of a special function lever which, when operated in response thereto, actuates a multi-armed lever, which, in turn, sets up six conditions; namely, first, a contact in the operating circuit for the start magnet of the transmitting distributor is opened to suspend transmission during "vertical tabulation"; second, the multi-armed lever is latched in its actuated position which condition is maintained during "vertical tabulation"; third, the line feed push bar is held in the path of the function bail; fourth, the main shaft clutch throwout lever is held released to permit continuous rotation of

the main shaft cam assembly during "vertical tabulation"; fifth, a universal function lever is held operated during the period of vertical tabulation to prevent printing and spacing; and sixth, the "letters" or unshift push bar is also held in the path of the function bail. While these six conditions are maintained, a succession of line feed operations is performed, and upon each line feed operation, a feeler lever is operated to sense the record material to find the control perforation therein. When the control perforation is found, the feeler drops therein, thus causing, through suitable linkage, the unlatching of the multi-armed lever which, in turn, permits the contact in the operating circuit of the transmitting distributor start magnet to close, to again start transmission, remove the line feed and unshift push bars from the path of the function bail, restore the clutch throwout lever to its stop position, and restore universal function lever which, during vertical tabulation, blocked printing and spacing.

The foregoing and other objects of the invention will be apparent from the following description when taken in conjunction with the accompanying drawings, wherein like reference characters designate similar parts throughout the several views, and in which

Fig. 1 is a perspective view of a mechanism according to the present invention, with a schematic diagram of a transmitter control circuit, only so much of the printing telegraph apparatus being shown as is necessary to an understanding of the invention;

Fig. 2 is a fragmentary perspective view of the main cam shaft showing the operative relationship between the clutch throwout lever and the vertical tabulator control mechanism;

Fig. 3 is a plan view of the record material used in carrying out the present invention;

Fig. 3A is an enlarged fragmental view of the record material showing the control hole;

Fig. 4 is a fragmentary view showing the relation between the selector mechanism and the automatic paper feeding mechanism according to the present invention;

Fig. 5 is a transverse cross-sectional view of the platen showing the paper sensing mechanism;

Fig. 6 is a perspective view of one modified form of paper sensing means; and

Fig. 7 is a schematic view of another modified form of the present invention.

Some of the novel features shown but not claimed herein are shown and claimed in the copending applications of A. H. Reiber, Serial No.

345,259, and of C. W. Burcky, Serial No. 345,258, both filed July 13, 1940.

Having reference particularly to Figs. 1 and 2, the mechanism according to the present invention is shown as embodied in a telegraph printing machine of the type disclosed in U. S. Patent No. 1,904,164, to which reference may be had for a detailed description of the printer elements. The selector mechanism is of the single magnet type and comprises a selector magnet 11 (Fig. 4) which is responsive to code combinations of signaling impulses. The magnet 11 has an armature 12 to which is fixed a lever 13. Lever 13 at its end adjacent to armature 12, is supported upon the pivot stud 14. A spring 15 has one of its ends secured to armature 12 and its other end secured to an adjusting screw 16. Normally the magnet 11 is energized and holds the armature 12 attracted against the pull of spring 15. The free end of lever 13 is provided with a pair of laterally extending arms or abutments 17 and 18, which cooperate with laterally projecting arms 19 and 21 on the rear ends of selector fingers or swords 22 to position the latter in their clockwise or counterclockwise position, as will presently appear.

Power for operating the selecting mechanism is supplied by a motor (not shown) to main shaft 23, Fig. 1, of the printer. Mounted near one end of shaft 23 is a selector cam barrel 24, which is frictionally connected to shaft 23 by means of suitable friction clutch members 20 (Fig. 2). The cam barrel 24 is provided with a helically arranged series of cams 25, one for each element of the permutation code. The series of cams 25 cooperate with a corresponding series of bell crank levers 26, pivoted on a common shaft 27 and normally biased clockwise, Fig. 2, by individual springs 28. Intermediate the arms 19 and 21 of swords 22 is a circular portion 29 adapted to fit into corresponding sockets in bell crank levers 26. By the action of cams 25 on bell crank levers 26, swords 22 are caused to thrust successively longitudinally of their lengths as the cam barrel 24 is rotated. In addition to this reciprocative movement, swords 22 have an oscillatory movement about circular portion 29 depending upon the cooperative relationship between abutting elements 17 and 19, and 18 and 21. A friction holding means (not shown) is provided to hold the swords 22 in the position to which they have been set. The springs 28 associated with bell crank levers 26 normally hold the swords 22 in their forward (rightward as viewed in Fig. 4) position and in engagement with a corresponding series of T-levers 31 pivoted at 32. Levers 31 are articulated to selector vanes 33 and rock said vanes to their clockwise or counterclockwise positions depending upon whether the swords strike them above or below the pivot shaft 32.

Selector lever 13 is also provided with an arm 34 terminating in an eccentrically headed adjustment screw 35, the function of which is to initiate, through a series of levers, the rotation of the selector cam barrel 24 in the following manner. Having reference to Fig. 4, it is observed that the head of screw 35 strikes against a plunger 36 slidably carried in a support 37 to actuate a trip member in the form of a small bell crank lever 38 pivotally mounted on shaft 39 so that its opposite arm may engage one arm of a latch 41 pivoted at 42 in a support 43 (Fig. 1). The extremity of the vertical arm of the bell crank 38 engages the latch 41 at a point coin-

ident with the axial center of shaft 23 and of a pivot stud 44 which is employed for orientation purposes, as fully set forth in said aforementioned patent. Latch 41 cooperates with arm 45 of a U-shaped stop gate 46 rotatably mounted on a pivot 47. Latch 41 is normally held in cooperative engagement with arm 45 of the stop gate 46 by a compression spring 48 (Fig. 1). Arm 49 of a stop gate 46 is adapted to be engaged by an arm 51 of stop disc 52 fixedly related to the cam barrel 24. Cam barrel 24 and stop disc 52 constantly tend to rotate (clockwise as viewed in Fig. 4) due to the frictional connection with constantly rotating shaft 23. Thus, stop disc 52, through its arm 51, tends to rotate stop gate 46 in a counterclockwise direction against the action of spring 53, but this movement is resisted by a shoulder 54 on latch 41. However, upon the receipt of a start or spacing signal impulse which is equivalent to an open line condition, the magnet 11 is deenergized and the selector arm or lever 13 is rotated clockwise, Fig. 2, under the action of spring 15. This causes the head of screw 35 to be actuated downwardly (as viewed in Fig. 4) to push plunger 36 correspondingly, thus imparting clockwise, Fig. 1, movement to bell crank 38, which causes latch 41 to rotate in a counterclockwise direction against the action of compression spring 48 sufficiently to withdraw shoulder 54 from cooperative engagement with arm 45. Stop gate 46 is free to respond to the greater pressure imposed upon it by stop arm 51 which overcomes spring 53. Stop gate 46 is thus rotated by arm 51 until arm 49 has become disengaged from arm 51, whereupon arm 51 and hence cam drum 24 continue to rotate during the ensuing cyclic period, and stop gate 46 is returned to its clockwise position (as viewed in Fig. 4) by spring 53. However, there is a slight overtravel of the stop gate 46 in its return movement, so that arm 45 will be moved clockwise sufficiently to permit the engagement of shoulders 54 and arm 45.

Upon receipt of a code combination of signal impulses, the start impulse serves to release armature 12, whereupon screw head 35 presses plunger 36 to effect, through levers 38 and 41, the removal of shoulder 54 from arm 45 so that arm 51 overcomes stop gate 46 counterclockwise and the rotation of cam drum 24 is initiated. During the ensuing single revolution of cam drum 24, the cam portions 25 thereon act sequentially on levers 26 to draw swords 22 leftwardly (as viewed in Fig. 4) so that abutments 19 and 21 thrust against arm 17 or 18, respectively, depending on whether lever 13 is in attracted or released position in response to the marking or spacing signal impulses, respectively, in the code signal. Swords 22 under the action of springs 28 act upon levers 31 to set the selector vanes 33 corresponding to the code signal received by the selector magnet 11.

Associated with selector vanes 33 are a plurality of function levers, one of which is the vertical tabulator function lever 55 and another of which is the universal function lever 60. The function levers are pivotally mounted on common shaft 56 and are provided with individual springs 57 which act upon selection to rotate the function levers clockwise (as viewed in Fig. 4) into cooperation with selector vanes 33. The function levers are held in their counterclockwise position by a rod 59 of a function lever bail, whose operation is controlled by the printing bail, as fully described in the aforementioned patent.

Function lever 55 is provided with a leftwardly extending arm 61 carrying at its extremity an adjustable striker screw 62 which cooperates with one arm 63 of a plural armed lever 64 pivoted on shaft 69. Also cooperating with arm 63 is a leftwardly extending arm (similar to arm 61) on the universal function lever 60. Lever 64 is provided with an arm 65 which extends underneath the unshift push bar 8 and the line feed push bar 66 (Fig. 1), and also a vertical arm 67 which terminates in a laterally disposed portion 50 adapted to engage with a latch member 68 pivoted on rod 71. Also pivoted on rod 71 is a U-shaped lever member 72 provided with a depending arm 73 and a horizontal arm 74. At the extremity of arm 73 there is pivoted the line feed push rod 66 which is provided at its free end with a shoulder 75 adapted to cooperate with the function bail blade 76, as described in the aforementioned patent. Arm 74 of the lever 72 has pivotally secured thereto one end of a line feed link 77, the other end of which is pivoted to the horizontal arm of a line feed bell crank lever 78, pivoted at 79. At the end of the vertical arm of the bell crank lever 78 is pivotally carried a line feed pawl 81 which cooperates with a line feed ratchet wheel 82 secured to a cylindrical platen 83.

Multi-armed lever 64 has also an arm 84 which serves to open the operating circuit of the start magnet of the transmitting distributor to suspend transmission during tabulation. Having reference to Fig. 1, the extremity of arm 84 of lever 64 overlies spring 85 of a normally closed contact 86, which is included in a circuit for energizing a stop magnet 60 of a transmitter distributor indicated generally by a dotted square 70, the transmitting contacts 80 of which are connected in a line wire 90 including selector magnet 11. Where operating conditions are encountered such that the speeds of the motors are determined by governors, and the governed motors of the printers in the circuit run at slightly different speeds, a time delay relay 231 may be introduced in the circuit for magnet 60, the purpose of which is to delay the resumption of transmission until the slowest printer in the circuit has completed vertical tabulation. The circuit for the stop magnet 60 extends from ground, through switch 180, relay 60, contact 86 and a contact 232 of relay 231 to battery. The circuit for relay 231 extends from battery, through relay 231, then through contact 233 to ground. During normal operation of printing, the switch 180 and contact 86 are closed, and the magnet 60 is energized, thus holding stop pawl 234 out of the path of the transmitting distributor brush arm 235. During vertical tabulation, the contact 86 will be held open by arm 84, and the contact 233 will be held closed. The opening of contact 86 causes the stop magnet 60 to become deenergized immediately. The closing of contact 233 completes the energizing circuit for the slow release relay 231, thus opening contact 232. Now, after completion of vertical tabulation, the contact 233 will be opened and the contact 86 will again be closed. However, the energizing circuit for start magnet 60 will not be completed until after the slow release relay 231 has become deenergized, thus delaying the closure of contact 232 and the energization of magnet 60 to resume transmission until the slowest printer in the line has finished the vertical tabulation operation.

Lateral portion 50, in addition to cooperating with latch 68, also cooperates with arm 87 of clutch throwout lever 88 pivotally mounted on 75

shaft 89, the other arm 90 of which cooperates with a sixth cam 91 on the cam drum 24 as set forth in the aforementioned patent. Arm 87 is provided with a lateral portion which is presentable into the path of a cam portion 92 of a jaw clutch 93, under the influence of a spring 94. Driving member 95 of jaw clutch 93 is fixed to shaft 23 and rotates constantly therewith. The driven portion comprising cam portion 92 is held by arm 87 in its leftward position against the action of a coiled spring 95. Latch member 68 has fixed thereto a stud 97 which fits into the lower forked end of a bar 98, the upper end of which is pivoted at 99 to the extremity of a lever 101 clamped to a pivot rod 102 carried by the printer frame. Fixed to link 77 is a member 103 having a laterally extending portion 104 positioned adjacent the lower side of lever 101 so as to impart rocking motion to lever 101 in response to the reciprocating movement of link 77 during the line feeding operations. A lever 105 is fixed to shaft 102 at the end opposite to lever 101 and is provided with arms 106, 107, and 108. To the extremity of arm 106 is attached one end of a spring 109, the other end of which is attached to a spring post 111 carried on the side frame 112 of the platen carriage. Arm 108 of lever 105 carries at its extremity a stud 113 which acts upon an arm 114 of a multi-armed lever 115 (as will presently appear) to rotate lever 115 clockwise about its pivot 116. Arm 107 of lever 105 is provided at its extremity with a laterally directed portion which cooperates with an arm 117 of lever 115. Lever 115 has also an arm 118 conformed at its extremity with a sensing portion or feeler 119 (Figs. 1 and 5), the function of which is to sense or search for a control perforation in the record material or printed form. The feeler 119 is receivable in a groove 121 in the platen 83 to provide clearance for the movement of the feeler 119 when a control perforation is found.

A guide member 122 is associated with the feeler 119 to facilitate the passage of the record material between said feeler and the platen 83. Guide 122 is provided with a notch or opening 123 to guide the feeler 119, and is integrally united with a lever arm 124 freely mounted on pivot 116. Lever 124 is normally biased counterclockwise by a spring 125 to press the guide 122 against the platen 83.

Lever 115 has also an arm 126 which terminates in a shoulder 127 which engages a latch arm 128 fixed to a rock shaft 129 to which a normal tendency to rotate in a counterclockwise direction is imparted by a spring 131. Lever 115 is normally biased in a counterclockwise direction by a spring 132 extending between a spring post secured to arm 126 and a spring post mounted on frame 112. Fixed to rock shaft 129 and in operative alignment with line feed bell crank lever 78 is an arm 133.

An arm 134 is freely mounted on rock shaft 129 adjacent the latch arm 128 and is pivotally articulated to one end of a link 135, the outer end of which is pivoted to arm 118 of lever 115. A stud 136 is secured to link 135 and overlies arm 124 and acts, when link 135 is moved downwardly, to rotate arm 124 clockwise against the tension of spring 125 moving guide 122 away from the platen 83 to facilitate the placing of record material in the printing apparatus preparatory to printing. Simultaneously, link 135 in its downward movement and due to its pivotal articulation with arm 118, rotates lever 115 so as

to bring feeler 119 out of contact with the record material as it is inserted between the platen and the guide 122. This downward movement of link 135 to facilitate the insertion of a new supply of record material is controlled by a cam portion 137 integral with a pressure roller lever 138 pivoted at 139 to the platen carriage frame 112. Lever 138 is normally spring biased by a spring (not shown) to hold pressure roller 141 against platen 83. When lever 138 is rotated to the dotted line position 142, the cam portion 137 acts upon arm 134 to depress link 135, thereby causing, through stud 136, the levers 115 and 124 to rotate clockwise to move guide 122 and feeler 119 away from platen 83 simultaneously.

General operation

The normal condition of the signal line is marking and hence the selector magnet 11 is energized and the armature 12 is held attracted. Upon receipt of the start impulse of a code combination the selector magnet is deenergized and lever 13 upon being actuated clockwise by spring 15 causes screwhead 35 to act through plunger 36 and levers 38 and 41 to release stop gate 46 to permit rotation of stop disc 52 and hence cam barrel 24, to effect, through levers 26, swords 22 and T-levers 31, the setting of vanes 33 in accordance with the received code signal. At a predetermined instant in the cycle of rotation of cam drum 24, cam 91 (Fig. 2) thereon acts upon arm 90 of clutch throwout lever 88 to rock the latter counterclockwise against the action of spring 94 to release arm 87 from cam portion 92 of clutch 93, thus permitting the driving and driven portions of clutch 93 to engage to initiate rotation of an operating cam assembly 100, a cam on which controls, through the printing bail, the operation of a function lever bail identified in Fig. 1 by the rod 59 for controlling the function levers, and another cam on which controls, through the function bail, a bail blade 76 for operating the function push bars; for example, line feed push bar 66 and the unshift push bar 8.

Upon receipt of a tabulator signal (for vertical tabulation or multiple line feed) which is an upper case signal (that is, the tabulator signal is preceded by a shift signal), the vanes 33 are set characteristically in the manner hereinbefore described, and upon operation of the function lever bail 59 the vertical tabulator function lever 55 will be selected and rotated about pivot rod 56 by spring 51 to raise arm 61 whereby, through screw 62, multi-armed lever 64 is rocked counterclockwise to bring portion 50 into latching engagement with the spring biased latch arm 68. Arm 65 of lever 64 raises line feed push bar 66 and unshift push bar 8 to bring the shoulders 75 thereof into the path of function bail blade 76 preparatory to performing a series of line feed operations as hereinafter set forth. Since the unshift push bar 8 was also raised to bring its shoulder 75 into the path of the function bail blade 76, it will be operated once upon the first oscillation of bail 76 in the tabulation cycle, to actuate the shift control lever (not shown) to return the platen to the "letters" or unshift position in the manner set forth in Patent 1,904,164. Arm 84 of lever 64 acts on contact spring 85 to open contact 86 and close contact 233 in the operating circuit for the start magnet 60 of the transmitting distributor (assuming switch 189 to have been previously closed) to suspend transmission during vertical tabulation in the manner

previously described. Portion 50 of lever 64 when latched up, acts to maintain arm 87 of clutch throwout lever 88 out of engagement with cam portion 92 of main shaft clutch 93, thus permitting the toothed portions of clutch 93 to engage to cause cam assembly 100 to rotate continuously. Thus, constant rotation of main operating cam assembly 100 causes the function bail 76 to be operated repeatedly.

Push bar 65, being held in the path of function bail blade 76, will be operated repeatedly, and through levers 72, link 71, bell crank lever 78, pawl 81 and ratchet wheel 82, will cause platen 83 to be line fed repeatedly. By this means and through the cooperation of sprocket feed pins 143 and pressure roller 141, the sprocket feed paper, as illustrated in Fig. 3, is fed through the printer.

Similarly, push bar 8, being held in the path of function bail blade 76, will also be operated once as previously described. This operation of push bar 8 after the initiation of the vertical tabulation function, besides acting to restore the printer platen 83 to the unshift or "letters case" position, automatically causes the lowermost of the vanes 33 (referred to in said patent as the sixth vane) to be rocked so as to prevent more than one selective operation of the vertical tabulator function lever 55. Furthermore, the latching-up of the multi-armed lever 64 has permitted the universal function lever 69 to be drawn by its spring (similar to spring 51) toward the selector vanes 33; the universal function lever 69 not being provided with code projections is selected whenever the restraint of arm 63 thereon is removed. The function of universal function lever 69 is to suppress, during the succession of line feeding operations, the printing and spacing functions in the manner set forth in said patent.

The record material employed in connection with the present invention constitutes preferably (though not necessarily) sprocket feed paper, as indicated in Fig. 3, comprising a series of blank forms 144 of the same standard length, which may have preprinted headings. To govern the feeding of the forms into proper printing position following the completion of the message recorded on the preceding form, a control hole or perforation 145 (Fig. 3) is provided in each form 144. The hole 145 is so positioned on the form 144 so as to coincide with the sensing portion 119 when the first typing line is at the printing point. As previously indicated, messages on each form 144 may contain different numbers of printed lines, and accordingly, before the first line of the next message may be printed, an additional feed must be imparted to the preceding message. This additional feed is initiated by the selection of the "vertical tabulator" function lever in response to the "vertical tabulator" code signal, as just described, and continues in response to repeated line feed operations until the control hole 145 is sensed by the feeler 119. It is, of course, obvious that more than one control hole 145 may be provided in each form, if desired.

Line feed of the platen 83 is effected in the direction of the arrow (Fig. 1) upon each downward movement of the link 71. As bell crank lever 78 is actuated counterclockwise, pawl 81 operates ratchet wheel 82 in the usual manner to effect a line feed of one step, and the vertical arm of lever 78 strikes the depending arm 133 to impart clockwise movement to rock shaft

129, thereby lifting latch arm 128 out of latching engagement with arm 126 of plural armed lever 115. Spring 132 will then urge lever 115 counterclockwise to bring feeler 119 into contact with the underside of the paper 144. The movements of the elements may be so timed that the feeler 119 will touch or sense the paper 144 during the rest period between successive line feed operations. With this arrangement, dragging of the sensing element upon the record material is avoided. If no hole 145 is positioned opposite feeler 119, only a limited rotation of lever 115 will result, and arm 117 thereof will still block arm 107, thus preventing shaft 102 from rotating clockwise sufficiently to cause, through arm 101, the bar 98 from unlatching arm 68 from arm 67 of plural armed lever 64 to stop "vertical tabulation."

When the line feed link 71 is returned to its upward position, lug 104 acts, through arm 101, to impart counterclockwise movement to shaft 102, to impart like movement to lever 105, so that stud 113 or arm 108 thereof acts on arm 114 to return lever 115 to its clockwise position, thereby permitting arm 126 to become again latched by latch arm 128.

If, when lever 115 is unlatched in response to a line feed operation, the feeler 119 senses a control perforation 145 and passes therethrough, lever 115 is caused to rotate counterclockwise a greater amount than otherwise to remove arm 117 out of blocking relation with arm 107, whereupon spring 109 is enabled to rotate lever 105, and hence shaft 102 a sufficient amount to depress bar 98 an extent great enough to unlatch arm 67 of plural armed lever 64. Upon being thus unlatched, lever 64 returns to the position shown in Fig. 1, to restore contact 86 to its closed condition and contact 233 to its open condition, thus resuming transmission; to drop push bars 66 and 80 out of the path of function bail blade 76; to permit clutch throwout lever 88 to return to its clockwise position under the influence of spring 94 to cooperate with cam portion 92 to effect the disengagement of the driving and driven portions of clutch 93, thereby preventing further rotation of cam assembly 100, and to restore universal function lever 60 to its unblocking position. The vertical tabulating mechanism according to the present invention is thus restored to its unoperated condition in readiness for a subsequent vertical tabulating signal. In the embodiment of the invention just described, the amount of movement of arm 107 (when unblocked) to effect the unlatching of arm 68 is independent of the degree of movement of sensing arm 119, thus increasing materially the margin of operation of the vertical tabulator.

Modifications

One modified form of page sensing mechanism is shown in Fig. 6 and contemplates the sensing of the control hole in the record material farther from the printing point and does not require grooving the platen for the feeler or stabber. In this form of the invention a line feed link 151 (comparable to link 71, Fig. 1) is pivoted to one arm of a line feed bell crank lever 152, to the vertical arm of which is pivoted a pawl 153 which cooperates with a ratchet wheel 154 fixed to the platen 155. A bar 156 (comparable to bar 98, Fig. 1) controls a latch similar to latch 68 of the principal embodiment of the invention, and is pivoted to an arm 157 fixed to

one end of a rock shaft 158, to the other end of which is secured a sensing lever 159 carrying at its outer extremity a feeler portion 161. Lever 159 is provided with an upstanding hook portion 162 which is engageable with a latch arm 163 pivoted at 164 to the platen carriage side frame 155. Lever 159 is also provided with a projection 166 to the end of which is fastened one end of a spring 167, the other end of which is attached to the latch arm 163. Spring 167 thus acts to bias lever 159 clockwise and to urge latch 163 clockwise into latching relation with hook portion 162. Latch arm 163 is provided with a projection 168 which cooperates with an arm 169 fixed to a rock shaft 171. Also carried securely on shaft 171 and positioned in cooperative relation with line feed bell crank 152 is a depending arm 172. A spring 173 attached to arm 169 tends to rotate shaft 171 normally in a counterclockwise direction. Fixed to shaft 158 is an arm 170 which engages lever 152.

The record material 174 of the form shown in Fig. 3 is fed between an apron or plate 175 and a guide plate 176. At a point coincident with feeler 161, plates 175 and 176 are perforated to permit the passage of said feeler therethrough when a control perforation similar to perforation 145 (Fig. 3) is found. The record material is directed around the platen 155, and engages the sprocket pins 177 in the usual manner.

Line feed of the platen 155 is achieved in the direction of the arrow (Fig. 6) upon each downward movement of link 151. As line feed lever 152 is operated counterclockwise, pawl 153 acts upon ratchet wheel 154 in the usual manner to effect a line feed of one step, and the vertical arm of lever 152 strikes the depending arm 172 to impart clockwise movement to rock shaft 171, thereby, through arm 169, swinging latch arm 163 out of latching engagement with sensing lever 159. Spring 167 will then urge lever 159 clockwise to bring feeler 161 into contact with the top side of the paper 174. If no hole 145 is positioned opposite feeler 161, only a limited rotation of lever 159 will occur and arm 157 will be prevented from rotating sufficiently to cause, through bar 156, the unlatching of the plural armed lever similar to lever 64 (Fig. 1).

When the line feed link 151 is returned to its upper position, the lever 152 acts, through arm 170, to impart counterclockwise movement to shaft 158, to impart like movement to lever 159 thereby permitting lever 159 to become latched again by latch arm 163. If, when lever 159 is unlatched in response to a line feed operation, the feeler 161 senses or finds a control perforation 145 and passes therethrough, lever 159 is caused to rotate clockwise a greater amount than previously, under the influence of spring 167, whereby shaft 158 is likewise rotated a sufficient amount to depress bar 156 an extent great enough to unlatch arm 67 (for example) of multi-armed lever 64 (Fig. 1), the effect of which is as described in connection with the principal embodiment of the invention.

According to another modified form of the present invention, the control of vertical tabulation by the sensing mechanism is effected electrically. Referring to Fig. 7, the selector vanes 181 (comparable to vanes 33, Fig. 1) are settable in code manner in response to received code combinations of impulses, in the manner set forth in connection with the principal embodiment, whereby the vertical tabulator function lever 182,

when selected, is rocked about pivot shaft 183 by spring 184 to raise its rearwardly extending arm 185. Resting on the end of arm 185 is a laterally disposed portion 186 of one arm of a lever 187, pivoted at 188, the oppositely directed arm of which is provided with a shoulder 189 which cooperates with the lower arm of a lever 191 pivoted at 192.

Lever 187 is also provided with a vertically extending arm 203 which terminates in a laterally disposed portion to cooperate with the clutch throwout lever 204, in a manner similar to that shown in Fig. 2 between portion 70 and arm 87. Lever 187 is normally biased clockwise by a spring 193 to cause portion 186 to follow arm 185. Overlying portion 186 is a line feed push bar 194 which is pivoted to the depending arm of a bell crank lever 195 mounted on a pivot shaft 196. To the horizontal arm of bell crank lever 195 is pivoted one end of a link 197, the other end being connected to the horizontal arm of a bell crank lever 198. A pawl 199 is pivoted to the vertical arm of bell crank lever 198 and cooperates with a ratchet wheel 201 to effect line feeding of platen 202.

Clutch throwout lever 204 governs the engagement of a clutch associated with a cam assembly 205 carried on main shaft 206 which, in turn, controls the rotation of function bail cam 207 to effect the operation of a function lever bail 208. Cooperating with the record material 144 is a contact 209 and a sensing lever 211 disposed thereabove. Lever 211 is fixed to a shaft 212 and is included in an obvious electrical circuit for operating an electromagnet 213. Electromagnet 213, when energized, causes lever 191 to rotate clockwise against the action of its spring 214. Spring 214 normally acts to hold the depending arm of lever 191 against the end of lever 187 in readiness to slip into the shoulder 189 when the lever 187 is actuated counterclockwise by function lever 182, as will presently appear. Sensing lever 211 is held out of sensing relation with the record material 144 by a latching lever 215 pivoted at 216, the arm 217 of which coacts with an arm 218 of a bell crank lever 219 pivoted at 221, the depending arm of which cooperates with the vertical arm of bell crank lever 198, in a manner similar to that described in connection with the modification shown in Fig. 6.

During the normal operation of the apparatus, the clutch throwout lever 204 is operated by a cam (similar to cam 91, Fig. 2) on the selector cam drum, as previously described. When the vertical tabulator signal is received, the selector vanes 181 are set accordingly to effect the selection of the vertical tabulator function lever 182 which, when the function lever bail 208 is operated, is permitted to rock clockwise under the influence of its spring 193 about the pivot 192 to raise the arm 185. Raising arm 185 in this manner imparts counterclockwise rotation to lever 187 against the action of its spring 193 about pivot 188. When lever 187 is so actuated, the line feed push bar 194 is raised to bring its shoulder 222 into the path of the function lever bail blade.

Also, lever 191 is permitted to engage shoulder 189 due to the action of spring 214 upon lever 191, since electromagnet 213 is at this time de-energized. Lever arm 203 acts to release clutch throwout lever 204 to permit the main shaft clutch to become engaged and to rotate continuously. This continuous rotation of the cam assembly 205 causes the function lever cam 207 to

actuate or rock the function bail 208 repeatedly, thereby imparting to the line feed push bar 194 repeated reciprocations. This action of line feed push bar 194 is imparted through bell crank lever 195 to the line feed link 197, and in turn to bell crank 198 and pawl 199, which, through ratchet wheel 201, imparts step-by-step rotation to platen 202, and accordingly moves the record material 144 past the contact 209 and sensing lever 211 in a step-by-step manner.

Each time the bell crank lever 198 is rocked counterclockwise for each line feed operation, it acts upon the depending arm of the lever 218 to cause, through arm 217, the latch 215 to become disengaged from the tape sensing lever 211. The tape sensing lever 211, each time it is disengaged or unlatched, will fall, due to the pull of its spring 210, upon the record material 144 seeking the control hole 145. The sensing function of lever 211 is performed momentarily between line feed operations, as is the case in the embodiment of the invention shown in Fig. 6. The lever 211 is fixed to shaft 212, to which is also fixed a lever (not shown) similar to lever 170 (Fig. 6) which overlies the horizontal arm of bell crank lever 198 so that, when the line feed bell crank lever 198 is returned to its clockwise position, counterclockwise movement will be imparted to lever 211, against the action of spring 210, whereupon lever 211 again becomes latched up by lever 215 preparatory to a succeeding line feed operation. When, in response to successive line feed operations, the sensing lever 211 finds a control hole 145, it falls therethrough and connects with the contact 209, thus completing an energizing circuit for the electromagnet 213. When the electromagnet 213 is energized, the lever 191 is rotated thereby in a clockwise direction against the action of its spring 214 to disengage the lower end thereof from the shoulder 189 of lever 187. Lever 187 then, due to the pull of spring 193, rotates clockwise to bring the line feed push bar 194 out of operative relation with the function bail 208. Arm 203 is also moved away from the clutch throwout lever 204, thereby permitting the clutch lever 204 to effectuate the disengagement of the clutch 205 in the manner shown in Fig. 2. The tape sensing lever 211 is returned to its latched position in the manner shown in the embodiment illustrated in Fig. 6 to effect the latching of said lever by the latch 215. The arrangement shown in Fig. 7 is now in a normal position preparatory to the reception of a subsequent vertical tabulator signal.

It is understood that the invention is not limited to the forms herein described, but embraces all forms and modifications which come within the scope of the appended claims.

What is claimed is:

1. In a printing telegraph apparatus, mechanism effective normally to advance a record strip step-by-step, signal controlled means, means releasable by said signal controlled means for operating said advancing mechanism, an instrumentality selectable by said signal controlled means, means operated by said instrumentality for controlling the consecutive operation of said advancing mechanism, and means controlled solely by a single designation in the record strip for interrupting said consecutive operation of said advancing mechanism at a point determined by the location of said designation in the record strip.
2. In a printing telegraph apparatus, mechanism effective normally to advance a record strip

step-by-step, signal controlled means, means releasable by said signal controlled means for operating said advancing mechanism, an instrumentality selectable by said signal controlled means, means operated by said instrumentality for controlling the consecutive operation of said advancing mechanism, and all-mechanical means controlled solely by a single designation in the record strip for interrupting said consecutive operation of said advancing mechanism at a point determined by the location of said designation in the record strip.

3. In a printing telegraph apparatus, mechanism effective normally to advance a record strip step-by-step, signal controlled means, means releasable by said signal controlled means for operating said advancing mechanism, an instrumentality selectable by said signal controlled means, means operated by said instrumentality for controlling the consecutive operation of said advancing mechanism, and electrical contact means controlled solely by a single designation in the record strip for interrupting said consecutive operation of said advancing mechanism at a point determined by the location of said designation in the record strip.

4. In a printing telegraph apparatus, mechanism effective normally to advance a record strip step by step, signal controlled means, an instrumentality selectable by said signal controlled means, a clutch operable to supply power to the record advancing mechanism, a clutch throwout lever normally holding said clutch disengaged, a trip lever included in the signal controlled means for rendering the clutch throwout lever ineffective to hold the clutch disengaged, means controlled

5 by the said instrumentality for also rendering the clutch throwout lever ineffective to hold the clutch disengaged, and means controlled solely by a single designation in the record strip to render the means controlled by the instrumentality ineffective for enabling the trip lever to control the clutch throwout lever.

10 5. In a printing telegraph apparatus, mechanism for advancing a record strip step by step, means for supplying power to said advancing mechanism, signal responsive means, an instrumentality selectable by said signal responsive means, means normally holding said power supplying means ineffective, tripping means for rendering said holding means ineffective, means under control of the instrumentality for rendering said holding means ineffective, and means controlled solely by a single designation in the record strip for rendering said holding means effective.

15 20 6. In a printing telegraph apparatus, mechanism for advancing a record strip step by step, means for supplying power to said advancing means, signal responsive means, an instrumentality selectable by said signal responsive means, means operable to render said power supplying means effective, means controlled by the signal responsive means for rendering said last mentioned means operable, means controlled by said instrumentality for holding operated the means for rendering the power supplying means effective, and means controlled solely by a single designation in the record strip for rendering the holding means inoperative.
